E. POSSON

SEALING LOCK AND DOOR STARTER

Original Filed Feb. 17, 1921

Inventor
Edward Posson
By Sheridan, Jones, Sheridan & Smith
Atty's.

UNITED STATES PATENT OFFICE.

EDWARD POSSON, OF CHICAGO, ILLINOIS.

SEALING LOCK AND DOOR STARTER.

Application filed February 17, 1921, Serial No. 445,592. Renewed August 11, 1924.

To all whom it may concern:

Be it known that I, EDWARD POSSON, a citizen of the United States, residing at Chicago, in the county of Cook and State of Illinois, have invented certain new and useful Improvements in Sealing Locks and Door Starters, of which the following is a specification.

This invention relates to improvements in apparatus for operating the sliding doors of railway cars and other like objects, where it is desirable to use means for effecting a positive movement of the door and securing the locking mechanism thereof in its closed position.

The principal object of the invention is to provide an improved combination sealing lock and door starter. A further object is to provide an improved form of operating mechanism for effecting a positive movement of the door to or from its closed position. A further object is to provide means for positively moving the door in combination with means for securely locking said moving means in a position corresponding to the closed position of the door. Still another object is to provide an improved form of operating lever for moving the door in combination with an improved bracket and locking bolt for securing the lever against movement. Other objects relate to various features of construction and arrangement which will appear more clearly hereinafter.

The nature of the invention will be understood from the following specification taken in connection with the accompanying drawings in which one embodiment is illustrated.

In the drawings—

Figure 1 shows a front elevation of a portion of a car door and the adjacent portion of the car wall, illustrating the application thereto of the improved door operating mechanism;

Fig. 2 is a longitudinal sectional view on the line 2—2 of Fig. 1, showing the top plan view of the door operating mechanism;

Fig. 3 is a vertical sectional view on the line 3—3 of Fig. 1, looking in the direction of the arrows;

Fig. 4 is a vertical sectional view on the line 4—4 of Fig. 1, looking in the direction of the arrows;

Fig. 5 is a vertical sectional view of the

line 5—5 of Fig. 1, looking in the direction of the arrows;

Fig. 6 shows a perspective view of the locking bolt; and

Fig. 7 shows a perspective view of the locking lever.

The invention is shown in connection with a car door 10 which is adapted to be hung in the usual manner by means of rollers adapted to travel on a horizontal track above the door opening. The leading edge of this door is adapted to seat against a door jamb 11 which is secured to the outer face of the vertical door post 12. The inside sheathing 13 and the outside sheathing 14 of the car wall terminate at and are secured to the door post 12, as shown in Fig. 2. The door jamb 11 is spaced longitudinally from the inner face of the door post and a vertical filler block 15 is inserted between the projecting portion of the door jamb and the adjacent portion of the car wall. A metal guide plate 16 is secured to the outer face of the door jamb 11 and projects beyond the edge thereof adjacent the door opening, thus forming a vertical guideway 17 between the plate and the door post to receive the leading edge of the door 10.

The door is operated by means of a lever 20 which is provided with an aperture 21 adapted to be loosely engaged by a pivot pin 22 which projects from a supporting member 23 carried by the car door. This supporting member seats against a plate 24, and a similar plate 25 is mounted on the inside of the door, the two plates and the supporting member 23 being secured to the car door by means of rivets 26. When the door is in its closed position, the lever 20 extends horizontally, as shown in Fig. 1, and projects beyond the door jamb so that the end portion 20^a thereof forms a handle to be engaged by the operator. A locking bracket 30 is seated on the outer side of the plate 16 and secured to the door post by means of a number of bolts or rivets 31 which extend through the door jamb and through the door post, as shown in Fig. 2. The bracket 30 consists of a plate 32 which seats against the vertical guide plate 16 and has formed thereon upper and lower guide members 33 and 34, respectively, which are provided with a vertical rectangular aper-

ture 35 therethrough to receive the vertical sliding locking bolt 36. Two of the bolts 31 by which the locking bracket is secured to the door jamb engage the ears 37 formed on the plate 32 and the other bolt 31 passes directly through the central part of the aperture 35 which is formed through the upper guide member 33. The locking bolt 36 is provided with a vertical slot 36^a adapted to receive the upper bolt 31, as shown in Figs. 1 and 3, and the locking bolt is further provided at its upper end with a transversely extending flange 36^b which engages the upper end of the guide member 33 to limit the downward movement of the bolt and to provide a handle by which the bolt may be manipulated by the operator.

This space between the upper and lower guide members 33 and 34 is adapted to receive the operating lever 20 and the plate 32 of the bracket is provided with a centrally located rectangular recess 38 which is adapted to receive the inwardly offset portion 40 of the locking lever 20. This offset portion 40 provides a notch 41 in the outer face of the lever, which notch is adapted to align with the vertical apertures 35 in the guide members 33 and 34, as illustrated particularly in Figs. 1 and 3. After the lever has been inserted into the recess 38 and the bolt 36 dropped downwardly, the bolt may be securely held in its downward position by means of the usual car seal which may be passed through the transverse slot 36^c in the lower end of the bolt and through the alining apertures 42 which are formed in the lateral walls of the guide member 34.

The locking lever 20 is provided with an arm 44 which projects upwardly from the pivot pin 22 and away from the door post, as shown in Fig. 1. The upper end of the arm 44 is provided with a projecting pivot pin 45 which forms a loose pivotal engagement with one end of a rod or arm 46. This arm is provided with a downwardly turned extremity 46^a which is adapted to engage an eye 47 formed on the bracket 30.

Assuming that the door is in its closed position, the operator after breaking the seal, moves the locking bolt 36 upwardly until the lower end thereof clears the locking lever 20. Then after moving the lever outwardly until it clears the bracket, a downward movement of the lever 20 will cause the pivotal point 45 to move to the right while the arm 44 and the rod 46 will operate in connection with the door post to facilitate the easy opening of the door. After the door has been started from its closed position, the rod 46 can be disengaged from the eye 47 and the door will then be free to pass to its full open position. When the door is being moved to its closed position, the rod 46 is first passed into engagement with the eye 47, after which an upward

movement of the handle 20^a will force the leading edge of the door into the guideway 17 and seat it firmly against the door jamb 11. The lever can then be swung into position between the upper and lower guideways of the bracket to permit the downward movement of the locking bolt 36.

Although I have shown and described one form of my invention for purposes of illustration, it will be seen that it may be constructed in various other forms without departing from the scope of the appended claims.

I claim:

1. In an operating and locking mechanism for a sliding door member having a frame member associated therewith, the combination with an operating lever pivotally mounted on one of said members; of means swingable in a plane substantially parallel to the plane of the door, and directly actuated by said lever, for detachably connecting the lever to the other member; and means for locking said lever in fixed position to lock the sliding door member.

2. In an operating mechanism for a door member having a relatively fixed abutment member associated therewith, the combination with a door operating element mounted on one of said members and movable in a plane substantially parallel with respect thereto; means for locking said element to one of said members; and a link element for directly connecting said operating element to the other of said members.

3. In an operating and locking mechanism for relatively movable door members, the combination with an actuating means mounted on one of said members; of means pivotally connected to said actuating means for detachably connecting the same to the other member; and independent means for locking said actuating means to hold the door in fixed position.

4. In a device of the character described, the combination with a frame member; of a door member; an operating element pivoted on one of said members intermediate its ends; means pivoted to an end portion of said element for connecting the same to the other member; and operating means for detachably locking said operating element to said last named member.

5. In combination, a frame member, a door, an operating member pivoted on said door, means for locking said operating member to said frame member, and independent means for connecting said operating member to said frame member.

6. In combination, a frame member, a door, an operating member pivoted on said door, means for forming a connection between said operating member and said frame member at one side of its pivotal axis, and separate means for detachably locking said

- operating member on said frame member at the other side of its pivotal axis.
7. In combination, a frame member, a door, an operating member pivotally mounted on said door, means for detachably forming a rigid connection between said frame member and said operating member at one side of its pivotal axis, and means for detachably forming a locking connection between said frame member and said operating member at the other side of its pivotal axis.
8. In combination, a vertical frame member, a door movable with respect to said frame member, an operating member pivoted on said door, a rod detachably connecting one end of said lever with said frame member, and locking means for detachably securing the other end of said lever to said frame member independently of the connection of said rod with said frame member.
9. In combination, a frame member, a door, a lever pivoted on said door, said lever having a transversely extending arm, means for connecting said arm to said frame member, and independent means for detachably locking the body portion of said lever to said frame member.
10. In combination, a frame member, a door, a lever loosely pivoted on said door, a bracket mounted on said frame member and having a recess to receive said lever, means for locking said lever in said recess, and independent means for connecting said lever to said frame member at the other side of its pivotal axis.
11. In combination, a door, a frame member, a lever loosely pivoted on said door, a bracket having a recess in its outer side to receive said lever, said lever having a notch, and a locking bolt slidably mounted on said bracket to engage said notch in said lever.
12. In combination, a door, a frame member, a lever loosely pivoted on said door, a bracket having a recess in its outer side to receive said lever, a locking bolt movable vertically on said bracket and adapted to pass on the outer side of said lever for securing said lever to said bracket, said lever having shoulders adapted to engage opposite sides of said bolt, and means for securing said bolt in its locking position.
13. In combination, a vertical frame member, a door movable with respect to said frame member, a horizontally extending lever pivoted on said door and extending beyond said frame member, a bracket secured to said frame member and having a recess therein, said lever having a part adapted to engage said recess, and movable locking
- means carried by said bracket and adapted to project on the outer side of said lever opposite said recess.
14. In combination, a frame member, a door, a lever connected to said door and extending alongside of said frame member, a guide member carried by said frame member, and a locking bolt mounted in said guide member, said lever having a notch adapted to receive said locking bolt.
15. In combination, a frame member, a door, a lever pivoted on said door and extending alongside of said frame member, a pair of guide members mounted on said frame member and adapted to receive said lever between them, a bolt slideable in said guide members and adapted to extend on the outer side of said lever, said bolt being provided with a longitudinal slot, and a pin engaging said slot.
16. In combination, a frame member, a door, a lever pivoted on said door and extending alongside of said frame member, a pair of guide members mounted on said frame member and adapted to receive said lever between them, a bolt slideable in said guide members and adapted to extend on the outer side of said lever, said bolt being provided with a longitudinal slot, and a pin engaging said slot, said bolt and one of said guide members being provided with alining apertures adapted to receive a car seal.
17. In combination, a frame member, a door movable with respect to said frame member, a lever pivoted on said door, said lever having an arm extending transversely from its pivotal axis, a bracket mounted on said frame member, an apertured member carried by said bracket, a rod pivoted to said arm of said lever and having a hooked extremity member adapted to engage said apertured member, and means carried by said bracket for locking said lever thereto.
18. In combination, a frame member, a door movable with respect to said frame member, a lever pivoted on said door, said lever having an arm extending transversely from its pivotal axis, a bracket mounted on said frame member, an apertured member carried by said bracket, a rod pivoted to said arm of said lever and having a hooked extremity member adapted to engage said apertured member, and a sliding bolt mounted on said bracket and adapted to extend on the outer side of said lever when said door is in closed position.

In testimony whereof, I have subscribed my name.

EDWARD POSSON.
